POWER TRANSMISSION

Hugh C. Nye, Detroit, Mich., assignor to Vickers
Incorporated, Detroit, Mich., a corporation of
Michigan

Application June 17, 1940, Serial No. 340,884

3 Claims. (Cl. 60—52)

This invention relates to power transmissions, particularly to those of the type comprising two or more fluid pressure energy translating devices, one of which may function as a pump and another as a fluid motor.

The invention is more particularly concerned with a power transmission system incorporating a differential-area, cylinder-and-piston motor together with control means for directing fluid to the opposite ends of the motor to produce feed and rapid-traverse movement with highest efficiency. In many classes of machine tools, for example, shapers, planers, and broaching machines, it is desirable to utilize a feed movement in one direction and a rapid-traverse movement in the other direction. At the same time it is likewise desirable to have the feeding movement take place in that direction in which the piston rod is in tension. This means that during the feeding movement, when the work to be done is usually the heaviest, the oil is fed into the small end of the cylinder where a given volume of fluid will produce a greater piston movement than in the large end. This drawback has heretofore been overcome by connecting both ends of the cylinder together during the return stroke so that the fluid discharged from the small end is added to the volume supplied to the large end. Such a system, however, does not provide independent control of the speed of movement in one direction as compared to that in the other direction where a fixed displacement pump is utilized as the source of supply.

Another method of providing for rapid-traverse and feed rates with a fixed displacement pump utilizes a flow-rate controlling mechanism for providing a reduced rate of fluid supply during the feeding movement, the excess volume delivered by the pump being bypassed without doing effective work. Systems of this character permit of ready control of the feeding speed without affecting the rapid return speed but have not heretofore utilized a differential cylinder action.

It is an object of the present invention to provide an improved power transmission system for operating a differential piston-and-cylinder motor in which the advantages of both methods of obtaining feed and rapid-traverse movement are utilized.

Further objects and advantages of the present invention will be apparent from the following description, reference being had to the accompanying drawing wherein a preferred form of the present invention is clearly shown.

In the drawing the single figure is a diagrammatic view of a power transmission system incorporating a preferred form of the present invention.

Referring now to the drawing, there is illustrated a differential-area piston-and-cylinder comprising a cylinder 10 having a piston 12 therein provided with a rod 14 projecting from one end of the cylinder. For the purpose of supplying fluid to operate the motor a fixed displacement pump 16 may be utilized and may be driven from a suitable prime mover such as an electric motor 18. Suitable overload relief mechanism 20 may be provided for limiting the maximum pressure produced by the pump 16. A suction conduit 22 connects the inlet of the pump with a tank or reservoir 24. From the outlet of the pump a supply conduit 26 connects directly and permanently with the small end of the cylinder 10.

A branch supply conduit 28 extends to one port 30 of a three-way directional-control valve designated 32. A second port 34 is connected with the tank by means of a conduit 36. The center port 38 of the valve 32 connects by means of a conduit 40 with the large end of the cylinder 10. The valve 32 may be provided with a longitudinally shiftable spool 42 having lands 44 and 46 adapted to selectively block either the port 30 or the port 34. In its mid position, illustrated, the spool 42 may connect all three ports together and thus effectively bypass the pump 16.

For the purpose of controlling the feeding movement of the piston 12 to the right, there is provided a branch circuit comprising a conduit 48 connected with the supply conduit 26 and leading to the inlet port 50 of a hydrostatic flow-regulating valve 52. Such a valve per se is well known in the art and may be constructed similarly to the valve illustrated in Figure 2 of British patent to Vickers, No. 399,609. It will suffice to state that the valve comprises a manually adjustable throttle 54 together with a hydrostatically regulated valve 56 which acts to maintain a

predetermined pressure drop across the throttle 54 thus maintaining constant the rate of flow through the valve for any given setting of the throttle 54. The outlet port 58 of the valve 52 connects by a conduit 60 with the conduit 40. Thus the conduits 48 and 60 and the valve 52 comprise a bypass across the two ends of the motor 10.

In operation, with the pump 16 running and the spool 42 in its central position, illustrated, the full discharge of the pump will be bypassed

to tank through conduit 28, ports 30 and 34 of valve 32 and conduit 36.

When it is desired to start the piston on a righthand feeding stroke, the spool 42 may be shifted to the right blocking port 30 and leaving port 38 connected to port 34. Under these conditions the full delivery of the pump is directed into conduit 26 where a portion of it goes into the small end of cylinder 10 and another portion passes to tank through the bypass 48-52-60 and through the valve 32.

Since the total volume delivered by the pump 16 is a constant value, the setting of the throttle 54 determines what proportion of that delivery is by-passed to the tank and consequently also determines the proportion which is directed to the cylinder 10. Thus by increasing the opening of the throttle 54 the speed of piston 12 will be slowed down and the opposite will be true when the throttle opening is decreased in size.

To cause a rapid return movement of the piston 12 to the left, the spool 42 may be shifted completely to its lefthand position blocking port 34 and leaving port 38 connected to port 30. Under these conditions pressures are equal in the conduits 26, 28, 40, 48 and 60 since all are connected to the outlet of the pump through freely open passages. The full volume of the pump passes through conduit 28, valve 32 and conduit 40 to the large end of cylinder 10. Piston 12 accordingly moves to the left discharging oil through conduit 26 where it joins with the pump delivery and enters the conduit 28, thus adding to the volume delivered to the head end of cylinder 10. It will be seen that under these conditions, since the pressure in conduits 48 and 60 is equal, there will be no flow through the flow control valve 52 because there is no pressure differential to create such flow. In other words, during leftward movement of the piston 12 the by-pass constituted by the conduits 48 and 60 is ineffective although it is open to the same extent as it was during feeding movement to the right.

It will thus be seen that the present invention provides an extremely simple circuit utilizing the advantages of differential cylinder action together with the advantages of a flow-rate controller with a fixed displacement pump.

While the form of embodiment of the invention as herein disclosed constitutes a preferred form, it is to be understood that other forms might be adopted, all coming within the scope of the claims which follow.

What is claimed is as follows:

1. A hydraulic power transmission system com-

prising in combination a differential-area cylinder-and-piston motor, a fixed displacement pump for supplying fluid to the motor, a conduit forming a permanently open supply line between the pump outlet and the small end of the motor, means for selectively connecting the large end of the motor with either the inlet of the pump for a forward feeding stroke or the outlet of the pump for a rapid return stroke, a by-pass permanently connecting the two ends of the motor, and a flow regulating valve in the by-pass effective to bleed a predetermined portion of the volume of fluid delivered by the pump during feeding movement, and ineffective during the rapid return stroke.

2. A hydraulic power transmission system comprising in combination a differential-area cylinder-and-piston motor, a fixed displacement pump for supplying fluid to the motor, a conduit forming a permanently open supply line between the pump outlet and the small end of the motor, a valve connected with the large end of the motor and with the pump inlet and outlet and effective in one position to connect the large end of the motor with the pump inlet for forward feeding stroke, in a second position to connect the large end of the motor with the pump outlet for a rapid return stroke, and in a third position to connect the pump inlet and outlet together to stop the motor, a by-pass permanently connecting the two ends of the motor, and a flow regulating valve in the by-pass effective to bleed a predetermined portion of the volume of fluid delivered by the pump during feeding movement, and ineffective during the rapid return stroke and while the motor is stopped.

3. A hydraulic power transmission system comprising in combination a differential-area cylinder-and-piston motor, a fixed displacement pump for supplying fluid to the motor, a conduit forming a permanently open supply line between the pump outlet and the small end of the motor, means for selectively connecting the large end of the motor with either the inlet of the pump for a forward feeding stroke or the outlet of the pump for a rapid return stroke, and a conduit forming a by-pass including means for producing a regulated reduced rate of flow therethrough, said by-pass being controlled by said selective connecting means and providing therewith a path connecting at one end to the pump outlet and at the other end to the pump inlet during the feeding stroke, one of said connections at one end of said path being interrupted during the rapid return stroke.
